UNITED STATES PATENT OFFICE.

JOHN H. GOODFELLOW, OF LOWELL, MASSACHUSETTS, ASSIGNOR TO THE LAMSON CONSOLIDATED STORE SERVICE COMPANY, OF NEW JERSEY.

STORE-SERVICE APPARATUS.

SPECIFICATION forming part of Letters Patent No. 608,595, dated August 9, 1898.

Application filed May 12, 1896. Serial No. 591,308. (No model.)

To all whom it may concern:

Be it known that I, JOHN H. GOODFELLOW, of Lowell, in the county of Middlesex and State of Massachusetts, have invented a new and useful Improvement in Store-Service Apparatus, of which the following, taken in connection with the accompanying drawings, is a specification.

This invention relates to improvements in store-service apparatus of that description in which the carrier is mounted on a way and is adapted to engage with a propelling-wire and is put in motion by the separation of the propelling-wire from the way. It more particularly relates to improvements in the mechanism for operating the propelling-wire and for receiving the carrier at the end of a trip.

The invention consists in the novel construction, combination, and arrangement of parts, such as will be hereinafter fully described, pointed out in the appended claims, and illustrated in the accompanying drawings.

25 In the accompanying drawings, Figure 1 is a side elevation of a store-service apparatus embodying the invention. Fig. 2 is a plan view of the same. Fig. 3 is a sectional view on the line 3 3 of Fig. 2.

30 Similar letters of reference designate corresponding parts in the several views.

A standard A is secured to a support of any construction suitable in the premises. It carries at its lower end the step a. Attached to the forward end of the step is one end of the way B. The other end of the way is secured in any suitable manner. Projecting from the upper face of the step a is a recessed lug a', provided with a set-screw a².

40 A bracket C is adjustably mounted on the standard A. It has a collar c' encircling the standard and a set-screw c² passing through a side of said collar and impinging on the periphery of the standard. By means of the set-screw the bracket can be secured in its adjustments on the standard. A hood c³ projects from the under side of the bracket and has journaled therein the sheave c⁴.

45 From the hood a rope-guide c⁵ extends. In 50 the collar c⁶, carried by the outer end of the bracket C, is mounted the upper end of the

guide-rod D. The lower end d of the latter is bent at substantially right angles to the upper part of the rod and is seated in the recess in the lug a', wherein it is adjustably secured by the set-screw a².

55 On the guide-rod D a sliding block E is mounted. From the rear of the block a recessed lug e projects. In the recess in the said lug is secured an end of the operating cord or rope e². The latter passes upward through the guide c⁵, over the sheave c⁴, and downward through an opening in the step a and has attached to its free end the handle e³. By means of this cord the sliding block 65 may be moved on the guide-rod.

60 Hinged on each side of the step a is a jaw F. A knuckle-joint f connects one end of the jaw to the heel of the step. These jaws are normally held apart at their free ends by the 70 spring f', interposed between them. Their movement apart is limited by the stops f², projecting from the cross-bar f³, secured to the under side of the step by the screw f⁴. They are prevented from moving vertically 75 by the said cross-bar and the lugs f⁵, projecting from the sides of the step. The movement of the jaws toward each other is limited by the step a, with which they contact when brought together. The outer or free ends of 80 the jaws are elongated and somewhat elastic, and at their outer ends, as at f⁶, they diverge, as shown in Fig. 2. The inner diverging faces of the jaws have secured thereto strips of leather f⁷.

85 The propelling-wire H is normally substantially parallel with the way B and is secured at one end to the eye e⁴, carried by the sliding block E. The other end of the wire is secured in any suitable manner. The end of the wire 90 engaging with the eye e⁴ is twisted to form a screw and has secured thereon the rubber buffer h. The screw formation of the wire serves to hold the buffer in place. As the guide-rod on which the sliding block moves 95 can be adjusted to or from the direction from which the wire approaches, the tension of the said wire can be regulated.

From the opposite sides of the sliding block E the curved arms e⁵ project. They extend outwardly and downwardly, as shown in Fig. 3, and form a yoke. Their lower ends di-

verge outwardly, as at e^6 . These arms or yoke when the sliding block is depressed engage with the free ends of the jaws F and force the latter together against the sides of the step a and also against the action of the spring f' .

A carriage K is mounted on the way B and engages with the propelling-wire H. It consists of the narrow elongated frame k' and has journaled in each end of said frame the upper and lower rollers k^2 and k^3 , respectively. To the under side of the carriage is removably attached the receptacle in any suitable manner. The dimensions of the frame k' are such that it will enter between the jaws F and be grasped by the latter, the said jaws springing apart slightly to admit the carriage.

The operation of the device is as follows: If the several operative parts should be in the relative positions shown in Fig. 1, except the carrier, and the latter should be started from the opposite end of the way, the frame k' would enter between the diverging ends f^6 of the jaws F and would strike against the leather-covered inner faces of the same. The impact of the frame on the jaws would force the latter apart, and the frame would enter between the jaws and be gradually stopped by the impact and the friction between the leather-covered faces of the jaws and the sides of the frame. If these obstacles should not be sufficient to entirely stop the carrier, further movement of the same would cause the frame to strike against the rubber buffer h on the propelling-wire. The carrier could not rebound after entering between the jaws, as the latter grasp the frame and hold the carrier.

To propel the carrier, the operator, through the cord e^2 , raises the sliding block E and thereby separates the propelling-wire from the way back of the upper and lower rollers mounted in the end of the frame k' . The upward movement of the sliding block releases the jaws F from the yoke formed of the arms e^5 and allows them to be forced apart by the spring f' and thereby frees the carriage from the jaws. The separating of the propelling-wire from the way back of the rollers of the carriage puts the latter in motion with a momentum sufficient to carry it to the other end of the way. When the cord is released, the movable parts resume their normal positions either by the action of gravity or their springs.

Having thus described the invention, what

I claim, and desire to secure by Letters Patent, is—

1. In a store-service apparatus, the combination of a way, a propelling-wire, means for separating said wire and said way, a carriage adapted to engage with said way and said wire, hinged jaws for engaging with said carriage, and a movable yoke for engaging with said jaws to hold the same closed. 65

2. In a store-service apparatus, the combination of a way, a propelling-wire, means for separating said way and said wire, a carriage adapted to engage with said way and said wire, hinged jaws for engaging with said carriage, a spring pressing said jaws apart, and a movable yoke for engaging with said jaws to hold the same together against the action of said spring. 70

3. In a store-service apparatus, the combination of a way, a propelling-wire, means for separating said way and said wire, a carriage adapted to engage with said way and said wire, hinged jaws for engaging with said carriage, a sliding block, and a yoke carried by said block for engaging with said jaws to hold the same closed. 75

4. In a store-service apparatus, the combination of a way, a propelling-wire, means for separating said way and said wire, a carriage adapted to engage with said way and said wire, hinged jaws for engaging with said carriage, an adjustable guide-rod, a block movably mounted on said rod, and a yoke carried by said block for engaging with said jaws to hold the same closed. 85

5. In a store-service apparatus, the combination of a standard, a step carried by the said standard, a way attached at one end to said step, a bracket mounted on said standard, a guide-rod carried by said step and said bracket, a sliding block mounted on said rod, means for moving said block, a propelling-wire connected at an end with said block, a carriage adapted to engage with said way and said wire, jaws hinged to said step for engaging with said carriage, and a yoke carried by said block for engaging with said jaws to hold the same closed. 95 100

In testimony whereof I have signed my name to this specification, in the presence of two subscribing witnesses, on this 4th day of May, A. D. 1896.

JOHN H. GOODFELLOW.
